UNITED STATES PATENT OFFICE.

JOHN C. FIDDYMENT, OF LOCKPORT, ILLINOIS, ASSIGNOR TO CONTINUOUS EXTRACTING PRESS CORPORATION, OF NEW YORK, N. Y., A CORPORATION OF VIRGINIA.

PRESS.

940,961.

Specification of Letters Patent. Patented Nov. 23, 1909.

Application filed November 30, 1908. Serial No. 465,154.

To all whom it may concern:

Be it known that I, JOHN C. FIDDYMENT, a citizen of the United States, residing at Lockport, in the county of Will and State 5 of Illinois, have invented a certain new and useful Press, of which the following is a specification, reference being had therein to the accompanying drawing.

This invention relates to presses of the 10 class known as expressing presses in which a screw is rotated within the press chamber to mash and compress the material and exert the requisite pressure thereon to force the liquid from such material through suitable 15 outlets in the wall of the press chamber.

The press is especially designed for extracting the liquid from vegetable seed, cotton seed, castor beans, nuts of various kinds, fish, brewers' products, and in fact any material 20 containing liquid capable of being expressed therefrom when subjected to pressure.

One object of the present invention is to provide means whereby, when material is 25 fed too rapidly or in too great a quantity into the press, the excessive pressure within the press chamber and the strain on the press chamber and other mechanism of the press will be automatically relieved.

Another object of the invention is to provide a novel initial feed whereby the material is primarily introduced into the press 30 under pressure, in connection with means whereby such pressure or the force of the feed and the rapidity of the same may be regulated to suit conditions.

Another object of the invention is to provide novel checking means acting to hold back the incoming material at intervals and 35 assist the main expressing screw to take up the material and advance the same through the press chamber.

A further object of the invention is to provide a practical and durable construction 40 of press chamber, whereby the bars or slats thereof are securely held in fixed position; also straining means so constructed and arranged relatively to the wall of the press chamber that the same may be removed and 45 replaced or renewed.

A further object of the invention is to provide a novel construction of thrust bear-

ing for withstanding the end thrust of the press chamber, said thrust bearing being capable of adjustment. 55

With the above and other objects in view, the invention consists in the novel construction, combination and arrangement of parts herein fully set forth, illustrated and claimed. 60

In the accompanying drawings:—Figure 1 is a side elevation of a press embodying the present invention. Fig. 2 is an enlarged detail section through the wall of the press chamber showing one of the relief 65 valves. Fig. 3 is a vertical longitudinal section through the press showing the main expressing screw, the checking device, etc. Fig. 4 is a detail plan view partly in section, showing the thrust bearing. Fig. 5 is an 70 end elevation of the press looking toward the receiving end thereof, with the adjacent portion of the press frame omitted. Fig. 6 is a detail perspective view of the end thrust bearing ring. Fig. 7 is a cross-section on 75 the line 7—7 of Fig. 3. Fig. 8 is a cross-section on the line 8—8 of Fig. 3. Fig. 9 is a detail perspective view of the stationary cam. Fig. 10 is a perspective view showing the check together with the flanges in connection with which the same co-operates. Fig. 11 is a detail perspective view illustrating the arrangement of feed throat leading into the space in which the expressing screw works. Fig. 12 is an enlarged vertical cross-section through the press chamber on the line 12—12 of Fig. 13. Fig. 13 is a vertical section through the same on the line 13—13 of Fig. 12. Fig. 14 is a detail perspective view of a portion of one of the bands or 80 hoops of the press chamber. Fig. 15 is a detail perspective view of one of the spacing blocks. Fig. 16 is a plan view of a portion of the inner wall of the press chamber, showing the straining means. Fig. 17 is a cross-section through the same. Fig. 18 is a view similar to Fig. 16 showing a slightly different arrangement of the straining means. Fig. 19 is a similar view showing another arrangement of straining means. Fig. 20 100 is a cross-section through Fig. 19. 95

Referring to the drawings, 1 designates the press chamber of an expressing press, and 2 the main shaft which passes length-

wise through the press chamber and has mounted thereon and rotating therewith the expressing screw by means of which the material in the press chamber is subjected 5 to the required pressure to express therefrom the liquid, which finds its way outward through openings 3 in the wall of the press chamber; these openings may be of any desired size, shape and character.

10 The screw shaft 2 is driven in any suitable way, as by means of the gearing 4 and the material is fed into the press chamber through a suitable hopper 5, while the several parts of the press may be mounted on a suitable frame 6.

In carrying out the present invention, the wall of the press chamber is provided at one or more points with openings 7 of a size adapted to receive and have fitted therein a 20 valve cage or casing 8 which may be threaded or otherwise fastened in place as shown in Fig. 2. The inner end of this valve cage lies flush with the inner surface of the press chamber and is partially closed by an annular flange 9, leaving an opening of the same size as the inner end of the valve 10, the inner wall of the flange 9 being beveled, as shown at 11.

Projecting outward from the valve 10 is 30 a stem 12 the outer end portion of which works through a guide 13 in the form of a cross bar held at a suitable distance from the outer surface of the press chamber by rods or bolts 14, parallel with each other and 35 fastened at their inner ends to the casing 8, as shown in Fig. 2. At an intermediate point in its length, the stem 12 is provided with a fixed cross head 15 which normally bears against stops or shoulders 16, preferably consisting of nuts adjustable on the rods 14 to permit the valve to be adjusted so that when the cross head 15 and stops 16 are 40 in contact with each other, the extreme inner face of the valve is just flush with the corresponding inner surface of the press chamber wall so as not to form any obstruction whatever to the free passage of the material 45 through the press chamber.

50 Springs 17 are placed around the rods 14 between the guide 13 and cross head 15, and the tension of these springs is exerted to hold the valve inward. When however the pressure of the material within the press chamber becomes excessive, the valve 10 overcomes the tension of the springs 17, which allows said valve to move outward 55 and permits a portion of the material to pass by the valve and escape. Nuts 18 on the rods 14, outside of the guide 13 provide for 60 adjusting the tension of the springs 17 to give more or less resistance to the outward movement of the valve 10. By the means hereinabove described excessive pressure within the press chamber is automatically 65 relieved.

The hopper 5 communicates with and discharges into a feeder casing 19 which is disposed about horizontally as shown in Figs. 5, 7 and 8, and within said casing is a rotary initial feed screw 20, one end of which extends out through the casing and carries a gear wheel 21 which meshes with and is driven by another gear wheel 22, interchangeable with other wheels of varying sizes so that by substitution of gears any desired speed may be imparted to the feed screw 20 to force the material with any required rapidity into the press with which the casing 19 communicates through an inlet opening 23, (see Fig. 8). Within the casing 19 is located a baffle 24 in the form of a fixed lug or projection, which holds the material from rotating with the screw, while the adjacent portion of the flight or thread of the screw is reduced in diameter, as shown in 70 75 80 85 said figure, to allow for the said baffle.

The expressing screw embodies the conico-cylindrical body 25 which increases in size toward the discharge end of the press, and the spiral thread or multiple flight 26, portions of which are reduced in diameter at intervals, as seen in Fig. 3, to allow for the location of baffles 27 to prevent the mass of material from following the screw around while being acted on and advanced thereby. 90 At its receiving end the screw 25 has fast thereon two parallel flanges 28 and 29 arranged at a distance from each other as best shown in Fig. 10. The inner flange 28 is cut away at one side to form a feed throat 100 30, which leads from the space between the two flanges, through the inner flange into the press chamber space occupied by the expressing screw. In forming the feed throat 30 the flange 28 is beveled off as shown at 105 31 so as to line up with the oblique face or wall 32, provided by leaving a part of the spaced between the innermost flights or threads 26 filled in as shown at 33.

Just opposite the feed throat 30, the flange 29 is apertured to receive a check or gate 34 which is pivotally connected to the flange 29 at 35, the axis on which the check swings being substantially radial to the shaft 2, as seen in Figs. 7. and 10. In cross section the check resembles a quadrant, as seen in Figs. 3 and 10, having oblique divergent opposite faces or sides, so disposed that when the outer side is flush with the outer side of the flange 29, the inner side extends obliquely 115 across the space between the two flanges 28 and 29, as shown in Fig. 3, in which position the check acts to divert the material and force the same through the feed throat 30 into the press chamber proper, where it enters between the flights or threads of the expressing screw and is taken up and carried on. As the shaft 2 continues to revolve, the inner side of the check rides against the edge 120 of a stationary abutment 36, which acts to 125 130

swing the check outward until the inner side of said check lies flush with the inner surface of the outer flange 29. The abutment 36 not only acts to throw the check outward but it constitutes a back stop to hold the material still while the check or gate acts on the material to force the same through the feed throat 30. Secured fast to the press chamber is a stationary cam 37 constructed and arranged to act on the check or gate 34 at the proper time to swing the same inward to the position shown in Fig. 3. Said cam may of course be mounted on any stationary part of the machine.

15 The wall of the press chamber is shown in Figs. 12 and 13, as composed of parallel bars or slats having their opposing side faces diverging outwardly. In order to securely hold the said bars or slats, bands or 20 hoops 38 are placed around the same at suitable intervals and the bars 39 are held relatively to each other and the hoops by means of spacing blocks 40, each comprising a substantially wedge-shaped body as shown in Figs. 25 12 and 15, and flanges 41 projecting from opposite sides of the outer and wider portion of the block. The wedge-shaped body of the block fits between adjacent bars 39 as seen in Fig. 12, the flanges 41 lying between 30 the bars and the inner surface of the adjacent band or hoop 38. The flanges 41 are oppositely notched as at 42 to permit the passage of the bolts 43 (see Fig. 12) which 35 connect the bands or hoops and bars and secure the press chamber structure together. To provide for setting the bolts 43 at any point around the hoops 38, the latter is provided with slots 44 through which said bolts pass. These slots may be of any suitable 40 length and are arranged to overlap as shown in Fig. 14, thus providing for setting the bolts at any point and at the same time avoiding weakening the hoops unnecessarily.

In order to provide for straining the material and separating the liquid therefrom, the inner surface of the press chamber wall is channeled as shown in Figs. 16 and 17, preferably in dove-tail form, and metal strips 45 are set into the channels, and being of corresponding dove-tail shape in cross section, they are thus held securely in place and yet capable of being easily removed. Fasteners such as screws 46 may also be used to hold the strips in place. Extending through 55 the wall in line with the channels are holes 47 through which the liquid passes, while in line with said openings the strips 45 are perforated or provided with strainer openings of any desired gage. In Fig. 16 the strips are shown as extending lengthwise of the press chamber, but they may extend around the inner wall of the press chamber as shown in Fig. 18. Another arrangement of strainer is shown in Figs. 19 and 20, in 60 65 which the press chamber wall is formed with

a number of circular holes each of which is rabbeted internally to form an annular shoulder 48 against which a corresponding shoulder on the strainer rests as shown in Fig. 20, the strainer being circular and fitting within said hole, and being held therein by a hollow cylindrical retainer 49, threaded into the hole, as shown.

70 By the arrangement just described, the strainers may be readily taken out and replaced or renewed when worn out and thus the inner surface of the press chamber wall may be kept in perfect working condition at small expense.

75 In actual work it has been found that there is an enormous end thrust on the shaft 2 and the press chamber 1. To take care of this, the shaft 2 is provided with a series of bearing shoulders 50 in the form of collars fast on said shaft, which are received in corresponding bearing recesses in the machine frame 6, as shown in Fig. 4. To take the end thrust of the press chamber a thrust bearing ring 51 is employed, the same having an annular flange 52 which fits over the extreme edge of said chamber as shown in Fig. 3. The ring 51 has oppositely projecting lugs 53 which carry adjusting devices for the ring, each consisting of a set screw 54 threaded into the lug 53, with the head 55 thereof bearing against the frame 6 as shown in Fig. 4. By turning the screws 54 any looseness between the end of the press chamber and the machine frame may be taken up, to give the proper bearing, and the screws may then be made fast by means of jam-nuts 56.

80 In connection with the feeder casing 19, it may be stated that the same may be imperforate, or perforated or of slatted construction to provide for the escape of liquid therefrom during the initial feeding operation.

105 I claim:

1. In an expressing press, a press chamber provided with a valved opening to allow for the escape of a portion of the compressed material for the purpose of relieving excessive pressure within the press chamber.

110 2. In an expressing press, a press chamber provided in the wall thereof with one or more pressure relief openings, each of which is controlled by a valve which operates automatically.

115 3. In an expressing press, a press chamber provided at intervals in its length with pressure relief openings, in combination with valve controlling said openings and adapted to be unseated by excessive pressure of the material within the press chamber.

120 4. In an expressing press, the combination with the wall of the press chamber, of means associated with said wall operating

- to relieve the excessive pressure of the material against said wall.
5. In an expressing press, a press chamber having an opening through the wall thereof, a pressure-relief valve controlling said opening, and means for regulating the degree of resistance of said valve.
6. In an expressing press, the combination with the press chamber, and the expressing screw, of a feed throat, and an oscillatory check or gate mounted on and carried around by said screw and operating to force material into said feed throat.
7. In an expressing press, the combination with the press chamber, and the expressing screw, of a feed throat, a check or gate carried around by the screw, and means operating during the rotation of said screw to swing the check or gate toward and away from the feed throat.
8. In an expressing press, a press chamber, an expressing screw working therein, circumferential flanges rotating with said screw, means for feeding the material into the space between said flanges, and means moving around with said flanges for intermittently delivering charges of the material from said space to the expressing screw.
9. In an expressing press, a press chamber, an expressing screw working therein, spaced parallel flanges carried by said screw, one of said flanges having a feed throat, means moving around with said flanges for feeding material into the space between said flanges, and an oscillatory check or gate operating at intervals to force said material through the feed throat and deliver the same to the expressing screw.
10. In an expressing press, a press chamber, an expressing screw working therein, spaced flanges carried with said screw, one of said flanges being provided with a feed throat, a pivoted check or gate carried around by one of said flanges and movable across the space between the flanges, a stationary abutment lying between said flanges and operating to swing the said check or gate in one direction, and means for swinging said check or gate in the reverse direction.
11. In an expressing press, a press chamber, an expressing screw working therein and provided with a pushing face between the flights or threads thereof, parallel flanges carried by said screw, one of said flanges having a feed throat, and a movable check or gate carried around by one of the flanges and operating between said flanges to force the material through the feed throat into the path of said pushing face.
12. In an expressing press, a press chamber embodying parallel bars or slats with intervening V-shaped spaces, correspondingly shaped spacing blocks interposed between said bars, and bands or hoops encircling the press chamber to hold the bars and blocks in place.
13. In an expressing press, a press chamber embodying parallel bars or slats, spacing blocks interposed between said bars and provided with flanges bearing against the outer sides of the bars, and bands or hoops encircling the press chamber and bearing against the flanges of the blocks.
14. In an expressing press, a press chamber embodying parallel bars or slats, spacing blocks interposed between said bars and provided with flanges bearing against the outer sides of the bars and having notches, bands or hoops encircling the press chamber and bearing against said flanges, and fasteners connecting the bars and bands and lying in said notches.
15. In an expressing press, a press chamber embodying parallel bars or slats, spacing blocks interposed between said bars, bands or hoops encircling the press chamber and provided with slots extending in parallel planes and overlapping each other, and fasteners connecting the bars and bands and passing through said slots.
16. In an expressing press, a press chamber the inside wall or surface of which is formed with channels, and openings through the press chamber in line with said channels, strainer strips lying flush within said channels, and means for fastening said strips in position so that they may be removed.
17. In an expressing press, a press chamber having outlet openings therein and channels formed in the inner surface thereof in line with said openings, and perforated strainer strips removably mounted in said channels with their inner surfaces flush with the inner surface of the press chamber.
18. In an expressing press, a press chamber the wall of which is provided with outlet openings for the liquid, strainers mounted to cover said openings and lie flush with the inner surface of said wall, and retaining means for holding the said strainers in place.
19. In an expressing press, the combination with the press chamber, of a thrust bearing therefor embodying a thrust ring against which the end of the press chamber bears, and adjusting means for said ring.
20. In an expressing press, the combination with the press chamber, of a thrust bearing therefor embodying a thrust ring, against which the end of the press chamber bears, and adjusting means for said ring consisting of one or more set screws interposed between said ring and a fixed part of the machine.
21. In an expressing press, the combination with the press chamber, of a thrust bearing therefor embodying a thrust ring against which the end of the press chamber bears, and adjusting means for said ring consist-

ing of one or more set screws interposed between the ring and a stationary part of the machine, and means for locking said screws.

22. In an expressing press, the combination with the press chamber, of a thrust bearing therefor embodying a thrust ring against which the end of the press chamber bears, a flange on said ring embracing the press chamber, and means for adjusting said 10 ring toward and away from the end of the press chamber.

23. In an expressing press, a press chamber having recesses in the wall thereof, and perforated metal screen sections held in said recesses and separated from each other by 15 portions of the press chamber walls.

In testimony whereof I affix my signature in presence of two witnesses.

JOHN C. FIDDYMENT.
